The design for an combined animal scratching pad and toy, as shown and described.

DESCRIPTION

FIG. 1 is a top plan view of an combined animal scratching pad and toy showing my new design with a scratching pad insert;

FIG. 2 is a right side elevational view thereof. The left side elevational view would be identical to the right side elevational view seen in FIG. 2;

FIG. 3 is a bottom view thereof;

FIG. 4 is a top elevational view of my new design with the scratch pad removed;

FIG. 5 is a cross-sectional view of the animal scratching pad and amusement device taken along line 5—5 of FIG. 1; and,

FIG. 6 is a cross-sectional view taken along section line 6—6 of FIG. 4.
